MUSICAL INSTRUMENT

Willie C. L. Morrison, Evergreen, Ala., assignor
of one-half to W. F. Kelley and J. E. Kelley,
Evergreen, Ala.

Application March 29, 1938, Serial No. 198,740

9 Claims. (Cl. 84—320)

This invention relates to a musical instrument, and has for its object to provide, in a manner as hereinafter set forth, a treadle operated and foot controlled stringed musical instrument.

5 A further object of the invention is to provide, in a manner as hereinafter set forth, an adjustable treadle operated stringed musical instrument including selectable actuated spring controlled foot operated fretting structures.

10 A further object of the invention is to provide, in a manner as hereinafter set forth, a musical instrument of the class referred to including a rotatable pick element common to the strings of the instrument and a treadle operated structure 15 for rotating said element.

A further object of the invention is to provide, in a manner as hereinafter set forth, a stringed instrument which is treadle operated and foot controlled for providing a guitar-like accompaniment for other musical instruments.

20 A further object of the invention is to provide, in a manner as hereinafter set forth, a treadle operated and foot controlled stringed instrument for providing a guitar-like accompaniment to another instrument, both operated simultaneously by the same player.

25 Further objects of the invention are to provide, in a manner as hereinafter set forth, a musical instrument for the purpose referred to which is comparatively simple in its construction and arrangement, strong, durable, compact, conveniently operated, readily assembled, tuned and adjusted, thoroughly efficient in its use, pleasing in tone, quickly repaired when occasion requires, and comparatively inexpensive to manufacture.

30 Embodying the aforesaid objects, and to others which may hereinafter appear, the invention consists of the novel construction, combination and arrangement of parts as will be more specifically referred to and illustrated in the accompanying drawings, wherein an embodiment of the invention is shown, but it is to be understood that changes, variations and modifications may be resorted to which fall within the scope of the 35 invention as claimed.

40 In the drawings:

Figure 1 is a top plan view of the instrument,
Figure 2 is an elevation looking towards one

end thereof,

45 Figure 3 is a fragmentary view in elevation looking towards the rear side of the bridge element,

Figure 4 is a section on line 4—4, Figure 3.

50 Figure 5 is a view similar to Figure 3 looking towards the front side of the bridge element,

Figure 6 is a section on line 6—6, Figure 1,
Figures 7, 8 and 9 are respectively sections on lines 1—1, 8—8, and 9—9, Figure 6,

Figure 10 is a section on line 10—10, Figure 9,
Figure 11 is a section on line 11—11, Figure 1,

Figures 12, 13, 14, 15, 16 and 17 are respectively sections on lines 12—12, 13—13, 14—14, 15—15, 16—16, and 17—17, Figure 11,

Figure 18 is a section on line 18—18, Figure 1,
Figure 19 is a section on line 19—19, Figure 1,

Figure 20 is a section on line 20—20, Figure 1,
Figure 21 is a fragmentary section on line 21—21, Figure 1, and

Figure 22 is a fragmentary section looking towards the inner end of the instrument.

15 The instrument includes an open top rectangular holder or base 21 having its sides 22, 23, its end 24 and its bottom 25 of skeleton form. The end 25 of holder 21 is open at its top. The holder may be constructed of any suitable material, 20 preferably light metal to enable for conveniently positioning the instrument at the point desired. The holder 21 at the bottom of its end 24 has connected therewith spaced bars which coact with the bottom of said end to form a rectangular skeleton support 26 having a portion disposed parallel to the bottom of the holder and its remaining portion disposed in outwardly directed lateral extended relation and at right angles to the side 23 of the holder. When the latter is 25 formed from light metallic material it is cast with the support 26 as an integral part thereof. The front end of support 26 is open and its rear end indicated at 27 closed.

30 Arranged within and supported by the holder 21 is a rectangular sound box 28 of thin wood having its corners reinforced by internally arranged braces 29 (Figure 20) secured thereto.

The bottom of box 28 is arranged above the bottom of holder 21. The top of box 28 is indicated 35 at 30 and constitutes a sound board. The top 30 at one end extends through the upper portion of and projects outwardly from the end 25 of holder 21 as at 31. The top 30 between its transverse median and what may be termed its head 40 or front end 32, is formed with a rectangular slot 33 transversely thereof and which is intersected at its transverse median by the longitudinal median of top 30. The latter between its transverse median and what may be termed its rear or inner 45 end 34 is provided with a circular opening 35 intersected centrally by the longitudinal median of the top 30. The end portion 31 is formed with four endwise aligned slots 36, 37, 38 and 39 for a purpose to be referred to. Arranged upon the 50

55 55

upper face of the top 30 of the sound box 28, is a short flat rectangular plate 40 constituting an anchor for one end of the strings of the instrument. The outer end of plate 40 is flush with the 5 end 32 of the said top 30. The plate 40 has its lengthwise center aligned with the lengthwise median of the said top 30 and is spaced outwardly from slot 33. The outer end terminal portion of plate 40, indicated at 41, is fixedly secured to 10 the said top 30 by the holdfast means 42. The inner end terminal portion of plate 40, indicated at 43, is formed adjacent to one side of the lengthwise median of the plate with a row of aligned spaced openings and with such openings 15 designated 44, 45 and 46. The said inner end terminal portion 43 is also formed with an opening 47 adjacent the other side of the lengthwise median of the plate.

Secured upon the said top 30 transversely 20 thereof and in proximity to and inwardly of the slots 36 to 39 in a combined guide and supporting member 48 having a high intermediate part 49 and a pair of lower end parts 50, 51. Secured in the part 49 is a plate 52 which extends above the 25 top edge 53 of the part 49 and constitutes a supporting ledge 54. The part 49 is formed with a triangular shaped cut-out 55 having its upper end opening at the edge 54 (Figure 21). Arranged outwardly with respect to the plate 52 and secured 30 to the edge 53 is a vertically disposed pin 56 located in proximity to one side of the open upper end of cut-out 55 and projecting above ledge 54. The plate 52 intersects the cut-out 55 and is formed with a pair of superposed openings 35 57, 58 which communicate with the cut-out 55. Secured to the bottom wall 59 of the cut-out 55 and located to one side of the openings 57, 58, is a vertically disposed pin 60. Secured to the part 51 is a plate 60^a which extends above the top edge 40 60^b of part 51 and provides a ledge 60^c. The part 51 has anchored in its top edge a pin 60^d which extends above the ledge 60^c.

Secured upon the said top 30, abutting the inner face of member 49 and extending in a direction towards the opening 35, is a pair of spaced parallel flat fret carriers 61, 62. The carrier 61 is of greater length than carrier 62 and is of a length to have its inner end to overlie a portion of opening 35. The inner end of carrier 61 is enlarged and substantially of quadrant-shaped contour as at 61^a. The carrier 61 has secured to and disposed transversely thereof, a set of spaced parallel frets 63, 64, and 65 which extend above the upper face thereof. The fret 64 is of greater 55 height than fret 63 and the fret 65 is of greater height than the fret 64. The distance between the latter and fret 63 is less than the distance between the fret 64 and the fret 65.

The carrier 62 consists of a pair of spaced parallel bar-like sections 66, 67 of like form and of a length to terminate at a point spaced from the opening 39. The sections 66, 67 have their lower lengthwise edges seated upon the said top 30. Each of said sections (Figure 11) is formed with 65 a tapered inner end terminal portion 68, spaced grooves 69, 70, 71 and 72 in its top edge 73 and spaced projections 74, 75, 76 extending upwardly from edge 73. The projections 74, 75, 76 have inclined lengthwise edges 77, 78, 79 respectively and vertical lengthwise edges 80, 81, 82 respectively. The direction of inclination of the said inclined edges is towards the upper ends of the said vertical edges. One wall of the groove 69 forms a continuation of the vertical edge 80 of 75 the projection 74. One wall of the groove 70

forms a continuation of the vertical edge of the projection 78. The projection 79 is arranged between and spaced from the grooves 70 and 71. The projection 78 is spaced from the groove 69. The grooves and projections of the section 66 5 align with the grooves and projections of the section 67. Secured to the aligned projections 74 near the upper ends thereof and bridging the space therebetween, is a pin-like fret 83. Secured to the sections 66, 67 directly below the projections 75 and bridging the space between said sections, is a pin-like fret 84 arranged between the grooves 69, 70. Secured to the aligned projections 76 and bridging the space between the latter, is a pair of spaced superposed pin-like 10 frets 85, 86. Secured to the sections 66, 67 directly below the projections 76 and bridging the space therebetween, as well as aligning in spaced relation with the fret 86, is a pin-like fret 87 arranged between the grooves 70, 71. Secured to the sections 66, 67 and bridging the space therebetween, is a pin-like fret 88 arranged between the grooves 71 and 72. The frets 83, 85 align with each other. The fret 84 is arranged in close proximity to the aligned grooves 70. The fret 87 20 is arranged in closed proximity to the aligned grooves 71, and the fret 88 is disposed in close proximity to the aligned grooves 72. The grooves 69 are of like width. The grooves 70 are of like width. The grooves 71 are of like width and the 30 grooves 72 of like width. The width of the grooves 70 is greater than any of the other grooves. All of the said grooves are of the same depth.

Secured upon the top edge of the side 23 of the frame 21 at a point between the slot 33 and plate 40, is an upstanding tubular bearing bracket 89 providing a bearing for a rotatable adjusting element 90 formed of a shank 91 having a smooth portion 92, a threaded portion 93 and a winged 40 head 94 integral with the outer end of shank 91. The smooth portion 92 of shank 91 is journaled in and extends inwardly from bracket 89. The head 94 is arranged against the outer side of bracket 89. The purpose of element 90 will be referred to. 45

The instrument includes a bridge element 95 for supporting the strings of the instrument in an elevated position with respect to the top 30 of the sound box 28. The element 95 is secured to the said top 29 between and spaced from the slot 33 and plate 40. The element 95 is disposed transversely of said top 29. The strings forming elements of the instrument correspond to the first (E), second (B), third (D) and fourth (A) strings of a guitar. The instrument is tuned as a Hawaiian guitar's second (C-sharp), third (A), fourth (E) and sixth (E) strings, this will match the chords on a Spanish guitar, violins and other instruments. The first string E, the second string B, the third string D and the fourth string A are indicated respectively at 96, 97, 98 and 99. One end of the strings 96, 97, 98 and 99 pass under the end terminal portion 43 of plate 40, then up through the openings 44, 45, 46 and 47 respectively and knotted and which in connection with plate 40 anchored the said end of the strings to the top 30 of the sound box 28. The manner in which the strings are arranged in relation to other elements of the structure will be presently referred to. 55

The bridge element 95 comprises a base 100 (Figure 6) formed in its upper face at one end of the latter with a recess 101 opening at the end edge 101^a of said base. The upper face of the latter inwardly of the recess 101 has formed 70 75

therein a rectangular cavity 102 which is connected to the recess 101 by a groove 103. Adjacent one side of and above the cavity 102, base 100 is provided with a ledge 104. Slidably mounted in the groove 103 and extending into the cavity 102 is an adjusting rod 105 for a yoke-shaped carrier 106 for the string 99. The carrier is capable of being selectively shifted in opposite directions by the rod 105 within the cavity 102. The ledge 104 supports the string 99 on the shifting of the latter by the carrier. The rod 105 is connected at one end to the carrier 106 and has its other end secured within an upstanding shifter 107 capable of being slid in opposite directions in the recess 101. The shifter at its upper end is mounted on and has threaded engagement with the threaded portion 93 of the shank 94. The rod 105 is retained in groove 103 by a keeper 108. The clockwise and anti-clockwise rotation of element 91 provides for the adjusting of the carrier in cavity 102.

The base 100 (Figures 3, 4 and 5) of bridge element 95 is formed with a narrow upstanding groove 109. The base 100 has mortised on the front face thereof, and extending across the groove 109, a vertically disposed plate 110 formed in its top edge with a groove 111 for the passage of string 96. The plate 110 below and aligning with groove 111 is provided with a pair of superposed openings 112, 113 for the passage of the strings 97, 98 respectively. The plate 110 not only acts as a support for holding the strings 96, 97, 98 over and in spaced relation to the top 29 of the sound box 28, but further acts to retain the said strings in superposed spaced relation. The plate 110 is secured to the base 100 by the holdfast means 114. The plate 110 is arranged between the cavity 102 and the end edge 115 of base 100.

40 The string 96 passes over and is disposed normally in spaced relation to the frets 83, 85, passes over and permanently seats on ledge 54 and bears against pin 56 (Figure 21). The string 97 passes over and is disposed normally in spaced relation to the fret 86 and extends through and bears against the bottom of the wall of opening 57 (Figure 21). The string 98 passes over and is disposed normally in spaced relation to the frets 84, 87, 88 and extends through and bears against the bottom of the wall of opening 58. The string 99 also bears against the pin 60. The string 99 passes over and is disposed normally in spaced relation to the frets 63, 64, 65, seats on ledge 60^c and bears against the pin 60^d.

55 Secured to the lower face of the extended end terminal portion 31 of the top 30 of the sound box 28 is a bar 115 formed with slots which register with the slots 36, 37, 38, 39. The bar 115 at its ends abuts the sides of the end 25^a of the holder 21. Carried by the bar 115 is a set of rotatable tuning devices 116, 117, 118, 119 for the strings 96, 97, 98 and 99 respectively which extend into the slots 36, 37, 38, 39 respectively and are connected to the shafts 120 of said devices.

65 These latter are of known form. Secured to the top edges of the sides of the holder 21 and disposed transversely of and spaced from the top 30 of box 28 is an arch 121 having depending centrally therefrom, a hanger 122 constituting a bearing for the inner end of a rotatable shaft 123 which carries and operates a pick 124. Carried by end 24 of the holder 21 is a bearing 125 through which extends the shaft 123. The support 26 includes a standard 126 which also provides a bearing for shaft 123. The

standard 126 is spaced from the end 24 of holder 21. Fixed to the shaft 123 between and spaced from the bearing 125 and standard 126 is a fly wheel 127 for the shaft 123. The latter outwardly of the wheel 127 is provided with a crank arm 5 128. Pivotal connected to the support 30, at the open end of the latter as at 129 and pivotally attached to the crank arm 128, is a foot treadle operated driving structure 130 for the shaft 123. The treadle element of the structure 10 130, indicated at 132 is provided with a retaining means 133 for the foot of the operator.

The pick 124 is arranged over and operates through the slot 33 in the top 30 of the sound box 28. The pick 124 is positioned between the superposed strings 96, 97, 98 and the string 99, and it includes a hub 134 adjustably secured on the shaft 123 by a set screw 135. Extending radially from the hub 134 is a curved picker-finger 136 having its width less than the length of the hub 134. The finger 136 is spaced equi-distant from the ends of the hub 134 and is of rectangular contour in cross section to provide a broad wiping surface for action on the strings to sound the notes. The finger 136 is of arcuate form with 25 its outer portion disposed in an opposite direction with respect to the direction of rotation of the shaft 123. The latter is driven in a clockwise direction. The finger 136 wipes successively on the strings 96, 97, 98 and then wipes the string 99. 30

The instrument includes a set of selectable spring controlled depressible foot operated fretting structures, three in number, indicated generally at 137, 138, 139, disposed transversely of and over the box 28, arranged in parallel relation and positioned between the opening 35 in box top 30 and the element 48.

The fretting structures 137, 138, 139 include depressible carriers 140, 141 and 142 respectively arranged in superposed spaced relation with respect to box top 30 and mounted adjacent to one end thereof on a common pivot 143 supported in the upper ends of vertical guides 144, 145, 146 respectively for the carriers 140, 141 and 142. The said guides are secured upon the top edge 45 of the side 22 of holder 21. The carriers at their pivoted ends extend through the guides. The other ends of the carriers are bifurcated as at 147. Vertically disposed selectively operated shift rods 148, 149, 150 are provided for the carriers 140, 141, 142 respectively. Each rod has its upper end extending into a bifurcated end of a carrier and is mounted on a pivot 151 which extends through the said bifurcated end. The carrier 141 is arranged between the carriers 140, 142. 50 The said rods are slidably mounted in the side 23 of holder 21 in the manner as is shown in Figure 20 with respect to the rod 150.

The carrier 140 has secured thereto and depending therefrom a fretting member 152 consisting of a strip 153 standing on its lower lengthwise edge and having extending therefrom spaced fingers 154, 155, 156, 157. The said fingers are disposed at right angles to strip 153, but finger 154 extends in an opposite direction to the direction in which the fingers 155, 156, 157 extend. The finger 154 is arranged over the fret carrier 61. The fingers 155, 156, 157 are arranged over the fret carrier 62. When carrier 140 is depressed the finger 154 is to coat with string 99 for moving it against fret 63, the finger 155 is to coat with string 96 for moving it against fret 83, the finger 156 is to coat with string 98 for moving it against fret 88 and the finger 157 is 75

to coact with string 97 for moving it against fret 84.

The carrier 141 has secured thereto and pending therefrom a fretting member 158 consisting of an upstanding strip 159 standing on its lower lengthwise edge and having extending therefrom spaced fingers 160, 161, 162. The said fingers are disposed at right angles to strip 159, but finger 160 extends in an opposite direction 10 to the direction in which the fingers 161, 162. The finger 160 is arranged over the fret carrier 61. The fingers 161, 162 are arranged over the fret carrier 62. When carrier 141 is depressed the finger 160 is to coact with the string 99 for 15 moving it against fret 64, the finger 161 is to coact with the string 96 for moving it against fret 85 and the finger 162 is to coact with the string 98 for moving it against fret 84.

The carrier 142 has secured thereto and pending therefrom a pair of oppositely disposed fretting members 163, 164 arranged over the fret carriers 61, 62 respectively. The member 163 includes a finger 165. The members 164 includes a body part 166 having extended thereof a set 25 of superposed spaced aligned fingers 167, 168, 169. When carrier 142 is depressed the finger 165 coacts with the string 99 for moving it against fret 65, and the fingers 167, 168, 169 coact respectively with the strings 96, 97, 98 for moving them 30 in unison against the frets 85, 86, 87 respectively.

The fretting members on the carriers are so related to provide for a clearance between them when one of the fretting structures is selectively depressed.

The shift rods for the carriers have fixedly secured thereto above their lower ends outwardly directed foot treads for the application thereto of pressure to lower the rods. The treads for 40 the rods 148, 149 and 150 are indicated at 170, 171, 172 respectively. The tread 172 is angularly disposed with respect to tread 171. Arranged below the treads 170, 171, 172 are controlling springs 173, 174, 175 respectively for normally 45 maintaining the rods 148, 149, 150 in their elevated position. When pressure is relieved on a tread, the spring for the latter will return the rod with which the tread is associated to its normal position whereby the fretting structure 50 is shifted upwardly on its pivot from active position. The said controlling springs are secured to the side 23 of holder 21 and extend outwardly from the latter. The form of the controlling springs employed is shown in Figure 20.

Anchored in the lower portion of the side 26 of the holder 21 is a positioning device 176 for that foot of the operator employed for selectively depressing a fretting structure. The device 176 extends outwardly from the side 26 of holder 21 60 and includes a pair of arms 177, 178 which are arranged between the tread 171 and the treads 170, 172.

On the operation of the shaft 123 in a clockwise direction, the pick 124 will be carried therewith and the finger 136 will successively wipe the strings 99, 96, 97, 98 to sound the notes. The notes may be changed by selectively depressing one of the fretting structures.

What I claim is:

70 1. A stringed musical instrument including a set of strings having the major portion of their length arranged in superposed spaced aligned relation, a single string having the major portion of its length disposed in parallel spaced relation 75 with respect to one of the strings of said set,

a rotatable pick arranged between said single string and said set of strings and including a radially disposed picker finger of a length for picking said single string and then successively picking the strings of said set from the uppermost to the lowermost string of the said set during the rotation of the pick, spaced frets arranged below and for coaction with said single string, other spaced frets arranged below and for coaction with the strings of said set, and 10 selectively operable spring controlled pivotally suspended fretting structures arranged over said single string and set of strings and each including fingers for depressing strings against frets. 15

2. A stringed musical instrument including a set of strings having the major portion of their length arranged in superposed spaced aligned relation, a single string having the major portion of its length disposed in parallel spaced relation with respect to one of the strings of said set 20 set, a rotatable pick arranged between said single string and said set of strings and including a radially disposed picker finger of a length for picking said single string and then successively picking the strings of said set from the uppermost to the lowermost string of the said set during the rotation of the pick, spaced frets arranged below and for coaction with said single string, other spaced frets arranged below and for coaction with the strings of said set, selectively 25 depressible spring controlled pivotally suspended fretting structures arranged over said single string and set of strings and each including fingers for depressing strings against frets, foot treads carried by said structures, a rotatable 30 shaft carrying said pick, and a foot operated driving means for said shaft.

3. A stringed musical instrument including a set of strings having the major portion of their length arranged in superposed spaced aligned 40 relation, a single string having the major portion of its length disposed in parallel spaced relation with respect to one of the strings of said set, a rotatable pick arranged between said single string and said set of strings and including a 45 radially disposed picker finger of a length for picking said single string and then successively picking the strings of said set from the uppermost to the lowermost string of the said set during the rotation of the pick, spaced frets arranged below and for coaction with said single string, other spaced frets arranged below and for coaction with the strings of said set, selectively 50 operable spring controlled pivotally suspended fretting structures arranged over said single string and set of strings and each including fingers for depressing strings against frets, spaced parallel supporting means for the major portion of the length of said single string and for maintaining said portion in spaced relation with respect to said set, and spaced parallel supporting means for normally maintaining the major portion of the length of the strings of said set in superposed spaced relation.

4. A stringed musical instrument including a set of strings having the major portion of their length arranged in superposed spaced aligned relation, a single string having the major portion of its length disposed in parallel spaced relation with respect to one of the strings of said set, 70 a rotatable pick arranged between said single string and said set of strings and including a radially disposed picker finger of a length for picking said single string and then successively picking the strings of said set from the upper- 75

most to the lowermost string of the said set during the rotation of the pick, spaced frets arranged below and for coaction with said single string, other spaced frets arranged below and for 5 coaction with the strings of said set, selectively operable spring controlled pivotally suspended fretting structures arranged over said single string and set of strings and each including fingers for depressing strings against frets, spaced 10 parallel supporting means for the major portion of the length of said single string and for maintaining said portion in spaced relation with respect to said set, spaced parallel supporting means for normally maintaining the major portion 15 of the length of the strings of said set in superposed spaced relation, and means connected to one of the supporting means for the major portion of the length of said single string for varying the space between such portion and the 20 said string of said set.

5. A stringed musical instrument including a set of strings having the major portion of their length arranged in superposed spaced aligned relation, a single string having the major portion of its length disposed in parallel spaced relation with respect to one of the strings of said set, a rotatable pick arranged between said single string and said set of strings and including a radially disposed picker finger of a length for 25 picking said single string and then successively picking the strings of said set from the uppermost to the lowermost string of the said set during the rotation of the pick, spaced frets arranged below and for coaction with said single 30 string, other spaced frets arranged below and for coaction with the strings of said set, selectively depressible spring controlled pivotally suspended fretting structures arranged over said single string and set of strings and each including fingers for depressing strings against frets, foot treads carried by said structures, a rotatable shaft carrying said pick, a foot operated driving means for said shaft, and a foot positioning means disposed in relation to said treads.

45. 6. A stringed musical instrument including a set of strings having the major portion of their length arranged in superposed spaced aligned relation, a single string having the major portion of its length disposed in parallel spaced relation with respect to one of the strings of said set, a rotatable pick arranged between said single string and said set of strings and including a radially disposed picker finger of a length for 50 picking said single string and then successively picking the strings of said set from the uppermost to the lowermost string of the said set during the rotation of the pick, spaced frets arranged below and for coaction with said single string, other spaced frets arranged below and for 55 coaction with the strings of said set, selectively operable spring controlled pivotally suspended fretting structures arranged over said single string and set of strings and each including fingers for depressing strings against frets, a sounding means arranged below said strings, means for anchoring the strings at one end to said means, means for adjustably connecting the other end 60 of the strings with said sounding means, a holder for said sounding means, a rotatable shaft arranged over said sounding means fixed to and bodily rotating said pick therewith, bearing means for said shaft carried by said holder, said structures being pivotally and slidably connected

to the holder, and a foot operating means for the shaft connected to the holder.

7. A stringed musical instrument including a set of strings having the major portion of their length arranged in superposed spaced aligned 5 relation, a single string having the major portion of its length disposed in parallel spaced relation with respect to one of the strings of said set, a rotatable pick arranged between said single string and said set of strings and including a radially disposed picker finger of a length for 10 picking said single string and then successively picking the strings of said set from the uppermost to the lowermost strings of the said set during the rotation of the pick, spaced frets arranged 15 below and for coaction with said single string, other spaced frets arranged below and for coaction with the strings of said set, selectively operable spring controlled pivotally suspended fretting structures arranged over said single 20 string and set of strings and each including fingers for depressing strings against frets, a sounding means arranged below and to which said strings are connected, a holder for said sounding means and to which said structures are pivotally 25 connected, and operating means for said pick supported by and connected to said holder.

8. In a stringed musical instrument, a sound box, a holder therefor, a set of superposed strings 30 and a single string spaced from said set, said single string and said set of strings connected with and having a portion of their length spaced above said box, frets on said box for coaction with said strings, selectable foot depressed spring 35 controlled fretting structure slidably and pivotally connected to said holder for coaction with said strings and frets, a horizontally disposed rotatable pick arranged between said single string and said set of strings and including a radially 40 disposed picker finger of a length for action on said single string and then for successive action on the strings of said set during the rotation of the pick, foot operated means connected to the holder for rotating said pick, and spaced means 45 for holding the portion of the length of the single string and strings of said set in spaced relation with respect to said box.

9. In a stringed musical instrument, a sound box, a holder therefor, a set of superposed strings 50 and a single string spaced from said set, said single string and said set of strings connected with and having a portion of their length spaced above said box, frets on said box for coaction with said strings, selectable foot depressed spring 55 controlled fretting structure slidably and pivotally connected to said holder for coaction with said strings and frets, a horizontally disposed rotatable pick arranged between said single string and said set of strings and including a radially 60 disposed picker finger of a length for action on said single string and then for successive action on the strings of said set during the rotation of the pick, foot operated means connected to the holder for rotating said pick, spaced means for 65 holding the portion of the length of the single string and strings of said set in spaced relation with respect to said box, means for anchoring one end of said strings to said box adjacent one end of the latter, and means for adjustably connecting the other end of the strings to the other 70 end of the box.

WILLIE C. L. MORRISON.
